UNITED STATES PATENT OFFICE.

LOWELL MASON MAXHAM, OF BOSTON, MASSACHUSETTS.

SELF-ACTING SAFETY APPLIANCE FOR STREET-CARS.

No. 866,595.

Specification of Letters Patent.

Patented Sept. 17, 1907.

Application filed May 14, 1907. Serial No. 373,698.

To all whom it may concern:

Be it known that I, LOWELL MASON MAXHAM, a citizen of the United States, and a resident of the city of Boston, in the county of Suffolk and Commonwealth of 5 Massachusetts, have invented certain new and useful Improvements in Self-Acting Safety Appliances for Street-Cars, of which the following is a full, clear, and exact description.

The object of this invention is the construction of improved means for cushioning a street car buffer; for locating a drop fender beneath the overhanging end-section of the car; for causing such fender to be dropped to the track when such cushion is struck; for causing the fender to be dropped through the action of a body lying 15 on the track immediately in front of the car, and for effecting other improvements in detail of construction hereinafter set forth.

Referring to the drawings forming part of this specification, Figure 1 is a perspective view of the front 20 portion of a street car provided with a life saving device embodying my improvements. Fig. 2 is a plan view of the front end of a street car platform, showing the buffer cushion in place. Fig. 3 is a side elevation of the street car front-section showing said cushion, the 25 drop-fender, and releasing devices for the fender. Fig. 4 is a front elevation showing the cushion-support, and the hand rail connected therewith. Fig. 5 is a perspective view of one of the castings by which the cushion is secured in place and the fender-dropping device 30 supported. Fig. 6 is a side sectional view of the buffer cushion. Fig. 7 is a side view of another form of pivot for the bail, in order to provide adjustment therefor.

The buffer cushion consists of the bar 1 lying upon the buffer of the car and having its extremities penetrated 35 by the vertical pins 8 projecting from the plates or brackets 10; the resilient arms 2, and the transverse slats 5 riveted to said arms. The upper section of each arm 2 is formed as an open loop 3 with its end suitably fixed to the bar 1. These loops are provided for the 40 purpose of giving a resilient support to the arms even when they happen to be struck upon a point directly in front of the bar 1.

A button 6 or other suitable lock is provided for insuring against the accidental dislodgment of the cushion 45 from the retaining pins 8. By simply turning said button, the cushion can be readily removed from said pins and placed within the car whenever it is desired to couple cars together and leave the buffers free to meet each other.

50 I prefer to provide a hand rail 7 above the cushion for the possible grasping by people who may be struck by the cushion, when the car is not in too rapid motion to render the action impossible.

Projecting from each plate or bracket 10 is a pin 55 11 formed with a suitable head, and upon these pins are pivoted the looped ends 16 of the uprights 15 forming a

portion of the swinging bail 14. The lower bar 17 of this bail is arranged to come sufficiently close to the track to be struck by any child who might be lying thereon, in order that the drop fender located behind 60 the same should be caused to drop to the track and such child, or any larger object, scooped up by the fender and preserved from injury.

The fender 20 is pivotally supported at 21 by the bar 22, and held normally out of contact with the track by 65 the notched arm 23 at each side engaging the rear extensions 25. Said arms are pivotally held by the cross shaft 24 having bearings in the braces 27 which are secured at their lower ends to the bars 22, while the upper ends of both such brace and bar are riveted or 70 otherwise fastened to the angle iron 28 secured to the under surface of the car sill. A spring 29 keeps said arms engaged with said extensions.

From each arm 23 a rod 30 extends forward through a suitable support 31 to the cushion aforesaid, being 75 there formed with a finger 33 bent in a direction to be engaged by some portion of said cushion. As illustrated, said fingers are bent upward and are engaged by the cross slat 5^a of the cushion. Consequently, whenever said cushion is struck a substantial blow, 80 as by some person falling against it, or being struck by the car, the yielding action of such cushion will be communicated through said rod or rods 30 to the arms 23, and thereby release the fender and permit it to drop to the track. When, now, such person falls to 85 the track, the fender will be ready to scoop him into its cradle. At the same time, said cushion acts to soften the blow which such person would otherwise have received from the car buffer, and saves him from the fractured skull which he might get from the 90 solid buffer.

Fixed to the uprights 15 is a cross bar 18 located close above the rods 30, and adapted to come against the shoulders 32 fixed on said rods, and to thereby move said rods rearward through any blow against the 95 bail 14, or any object lying upon the track as above described. By the backward swing given to said bail, and such movement of the rods 30, the fender will be released as before and permitted to drop to the track and scoop up the object contacting with said bail.

As is evident, the shoulder 32 in its rearward movement descends slightly, while the cross rod 18 swings upward as well as rearward. Consequently, after a sufficient movement of the rods 30 to release the fender, the cross rods 18 will escape from the shoulders 32 and 105 permit the bail 14 to swing backward and upward enough to avoid any interference with the passage of a large object, such as a fat person, back upon the fender cradle. The instant such object is scooped up, however, the bail falls upon it and in front of the same and 110 effectually prevents it from becoming dislodged from the fender. Cross bars 35 terminally held by the verti-

cal bars 22 keep any such object from passing on behind the fender.

I prefer to form the bail 14 with a second horizontal rod 17^a a short distance above the lower one 17, for the 5 purposes of improving the appearance of the bail, strengthening the same, and also to insure against the possibility of any child's falling over the lower rod 17 without contacting with it enough to drop the fender.

As shown in Fig. 3, the loop 16 at the end of each upper 10 right 15 is made in the shape of a shepherd's crook in order to permit of the bail's being removed from the headed pins 11 whenever desired, and especially whenever a person has been caught upon the fender. By removing the bail, such person can be easily taken 15 out from his awkward location. It is also necessary to vertically elongate the loops 16 to permit of the bail's being returned with greater ease to its normal position. The shoulders 32 being formed with oblique or slanting rear faces, the cross rod 18 slides up over the same 20 as the bail is being swung forward to its normal position, and such rising of the cross rod is permitted by the said vertical elongation of the loops 16. I further prefer to curve the lower corners of the bail outward, as shown in Fig. 1, in order to widen the same to a slight 25 distance beyond the sides of the car, and insure the fender's action even where the obstruction is but partially in the path of the car.

Instead of the loop 16, I prefer to cut the upright 15 off somewhat shorter, and have the same penetrate 30 the casting 16^a, and provide the latter with a set screw for adjustably holding such upright at any point of vertical position. The eye shown in said casting would be pivoted to the plate 10 by any suitable pin or bolt.

35 What I claim as my invention and for which I desire Letters Patent is as follows, to wit;—

1. The combination with a car, of a transverse bar, means normally holding said bar rigid with the buffer of the car but permitting its being lifted off therefrom, and a 40 resilient buffer cushion supported by said bar; whereby such cushion can be instantly removed without the use of tools to permit the buffer to be made clear for coupling to another car.

2. The combination with a car having vertical pins rising 45 above the upper surface of the buffer of said car, of a transverse bar penetrated by said pins and resting upon such surface, a lock retaining said bar in place, and a resilient cushion held by said bar.

3. The combination with a car having vertical pins rising 50 above the surface of the buffer of such car, of a transverse bar resting upon such surface and penetrated by said pins, a button for locking said bar in place, depending arms resilient at their upper ends and attached thereto to said bar, and cross slats secured to said arms.

4. The combination with a car, of brackets fixed to the front thereof, vertical pins rising from the forward parts of said brackets, a transverse bar penetrated by said pins and having its extremities supported by said brackets, and a resilient cushion held by said bar; whereby said bar and a cushion can be bodily removed without the use of tools.

5. The combination with a car, of a drop fender carried beneath its forward section, a lock normally holding said

fender from the track, an easily removable cushion guarding the car buffer, slideable rods adapted when moved rearward to release said lock, and a swinging bail hung close 65 behind said cushion and adapted when swung backward to engage said rods and cause them to release the lock; said cushion being also adapted to engage and actuate said rods; whereby the fender is dropped to the track either by the blow against said cushion of a person on his feet, or by the blow against the bail of a prostrate body.

6. The combination with a car, of a drop fender carried beneath its forward section, a locking device normally holding the fender from the track, longitudinally movable rods connected with said locking device, means for slidably supporting said rods, and a depending bail pivoted to the car front and adapted to momentarily engage said rods and move them and then to be disengaged therefrom, when it is swung backward; whereby not only is unimpeded access given to the fender, but the locking device is permitted to again engage and stop the fender from an unlimited upward movement should it rebound from its drop.

7. The combination with a car, of a drop fender carried beneath its end and having rearward extensions, notched swinging arms resiliently pressed into engagement with said extensions, a swinging bail depending from the car front, and means extending between said bail and arms for causing the rearward movement of said bail to release said arms from said extensions; said means being constructed to be engaged by said bail during the first part of the latter's swing and to be released during the remainder thereof, and so to leave said arms free to again lock the fender during such remainder of the swing.

8. The combination with a car, of a drop fender carried beneath its end, a locking device constructed to engage and lock said fender automatically against movement either up or down whenever the fender is in its normal position, a swinging bail depending from the car front, and means extending between said bail and locking device for causing the initial rearward movement of said bail to release said locking device; said means being constructed to be disengaged by said bail during the remainder of the latter's rearward swing and so to leave the locking device free to engage said fender.

9. The combination with a car, of a drop fender carried beneath its end, a locking device normally holding the fender from the track, longitudinally movable rods connected with said locking device, a depending bail pivoted to the car front, a shoulder on each of said rods, and means rigid with said bail adapted to engage said shoulders and move 100 said rods back to release said locking device, and to be disengaged from said shoulders immediately thereafter and so to permit said bail to freely swing backward.

10. The combination with a car, of a drop fender carried beneath its end, a locking device normally holding said fender from the track, a swinging bail pivoted at its upper ends to said car, connections between said bail and locking device whereby the rearward swing of said bail releases the drop fender from the locking device, the upper ends of said ball being capable of vertical adjustment.

11. The combination with a car, of a drop fender, and supporting means at each side comprising a vertical bar fastened to the car-sill, an oblique brace between said bar and sill, an arm pivoted to said brace and engaging the fender to normally support it from falling to the track, 125 and releasing means connected with said arms.

In testimony that I claim the foregoing invention, I have hereunto set my hand this 11th day of May, 1907.

LOWELL, MASON MAXHAM.
